UNITED STATES PATENT OFFICE.

CHARLES D. HERROLD, OF SAN JOSE, CALIFORNIA.

MAGNETIC LIFT FOR ELECTRODES IN ELECTRIC OSCILLATORS.

1,120,306.

Specification of Letters Patent.

Patented Dec. 8, 1914.

Application filed May 7, 1913. Serial No. 786,097.

To all whom it may concern:

Be it known that I, CHARLES D. HERROLD, a citizen of the United States, residing at San Jose, in the county of Santa Clara and State of California, have invented new and useful Improvements in Magnetic Lifts for Electrodes in Electric Oscillators, of which the following is a specification.

This invention relates to an apparatus for automatically lifting and separating the electrodes in an electric oscillator by means of electromagnetism.

The object of this invention is to provide an electric, automatic mechanism for the purpose of simultaneously lifting a plurality of electrodes in an oscillating circuit, and also for the purpose of adjusting the spacing between the electrodes where several electric oscillators are installed in a circuit.

The invention consists of the parts and the construction and combination of parts as hereinafter more fully described and claimed, having reference to the accompanying drawings, in which—

Figure 1 is a side elevation in section showing the application of the invention. Fig. 2 is a front view, partly in section, and a diagram showing the position of the mechanism with relation to the several apparatus used in wireless transmission. Fig. 3 is a plan view of Fig. 1.

In the operation of a number of high frequency oscillators it has been found that in order to produce uniform persistent undamped oscillations of high frequency, force and effect it was absolutely necessary that the electrodes in each oscillator should be provided with separate or independent adjustments for the purpose of adjusting the space between the electrodes in each separate oscillator. This is of great importance as it is otherwise practically impossible to produce synchronism of oscillation between the several oscillators in a circuit. The elimination of such independent adjustment between the electrodes will generally produce irregular oscillations which become quickly damped with a consequent loss of efficiency, and without an independent adjustment it can be seen by the eye that all the oscillators are not working alike; i. e., the sparking between the electrodes in each oscillator is different, and this can only be remedied by an independent adjustment, as it is found by observation and practice that each oscil-

lator requires a different distance between the electrodes.

Referring to the drawings: A and B indicate the containers of a pair of submerged oscillators connected in series, and C and C' indicate a pair of bracket members or supports which are adapted to be secured to the edges of the containers by any suitable means, or as here shown by the clamp screws 2.

Suitably secured upon the bracket members C and C' are a pair of solenoid lifting magnets 3 and 4, provided with movable cores 5 and 6, which are so positioned as to be lifted in an upward direction when the coils become energized, and which are normally adapted to rest upon brackets 7 when not acted on by the coils. The upward movement of the cores 5 and 6 within the coils is limited, and each core may be independently adjusted by stops 8, formed on the lower ends of adjusting screws 9 and 10, mounted in brackets 11 and 12, suitably secured upon the top portion of the coils 3 and 4. The outer ends of the brackets 11 and 12 are extended a suitable distance, as indicated at 13 in Figs. 1 and 3, to form guide members for the electrodes later to be described.

Centrally and vertically mounted within the containers A and B is a pair of stationary electrodes 14 and 15, and a pair of movable, adjustable electrodes 16 and 17.

The electrodes 16 and 17 are secured on the lower ends of a pair of downwardly extending rods 18 and 19, slidably mounted in the guide members 13, while the stationary electrodes are shown as secured upon the lower ends of downwardly extending brackets 20, secured at 21 to the main supporting brackets C and C'. The brackets 20 may be covered with any suitable form of insulating material, and are also adapted to act as conductors for the stationary electrodes, suitable connections as 22 being provided for this purpose.

Suitably secured on the lower ends of the cores 5 and 6, or formed integral with same, is a pair of right-angular extending magnetic clutches 23 and 24, provided at their outer ends with openings of sufficient size to permit insertion of the electrode carrying rods 18 and 19. The rods 18 and 19 are thus guided at two points, and are also adapted to be lifted by the clutches, as the rods will be instantly magnetically gripped.

by the clutches and lifted in unison with these the moment the coils or solenoids 3 and 4 become sufficiently energized to lift the cores within the coils; the upward movement of the cores 5 and 6 being limited by the adjustable stops 8. It thus becomes possible to adjust the spacing between the stationary and movable electrodes in each oscillator, and it also becomes possible to 10 vary the lift or spacing between electrodes in each oscillator by regulating the adjusting screws 9 and 10.

In operation, by referring to Fig. 2 of the drawings it will be seen that the coils or 15 solenoids 3 and 4 are connected in series upon the oscillating circuit of the system, and that the oscillators consisting of the stationary electrodes 14 and 15 and movable electrodes 16 and 17 are connected in series 20 upon the oscillating circuit of the system. The instant the controlling switch 25 is closed the circuit will be closed through the solenoids 3 and 4, and also through the oscillators. This will immediately energize 25 the coils 3 and 4, and cause the cores 5 and 6, with connected magnetic clutches 23 and 24, to grip the rods 18 and 19 and lift these in unison with the cores 5 and 6 until the upward limit of movement of same is 30 reached; this upward movement being, as before stated, controlled by the adjustable stops 8. The oscillating circuit, being simultaneously closed by the controlling switch 25, also becomes operative and sparking will 35 take place between the electrodes 14—16 and 15—17. Synchronism of oscillation between the electrodes may be observed by the eye; that is, if the sparking between the electrodes in each oscillator is different it is 40 immediately known that synchronism of oscillation is not taking place. This may, however, be instantly remedied by regulating the adjusting screws 9 and 10 until the 45 sparking between the electrodes is equalized, thus indicating that the desired adjustment has been secured.

The movable electrodes 16 and 17 in practice are generally formed of carbon and will 50 gradually burn away or shorten by the corrosive action of the arc or spark between the electrodes, so that the carbon electrodes in one oscillator may become shorter than in the other, thereby interfering with and decreasing the efficiency and constancy of the 55 oscillations. This would thus destroy the adjustment previously secured by adjusting the spacing of the electrodes, but may be instantly remedied by simply opening the controlling switch 25, which will cause the solenoids 60 to become deenergized and allow the rods 18 and 19 with connected electrodes to drop into contact with the stationary electrodes; the rods being released the moment the clutching magnets become deenergized. 65 By closing the controlling switch or circuit

through the solenoids 3 and 4, it will be seen that the coils will again become energized with the result that the rods will be instantly gripped and lifted in unison with the cores into the adjusted position previously secured, thus instantly establishing the desirable or more efficient spacing between the electrodes previously secured by the adjusting screws 9 and 10.

The apparatus here shown is simple and 75 compact in construction and may be easily removed as a unit from the containers at any time by releasing the clamping screws 2. It thus becomes possible to remove the electrodes for inspection or renewal without 80 disturbing the circuit connections to any extent.

The materials and finish of the several parts of the mechanism are such as experience and judgment of the manufacturer may 85 dictate.

Having thus described my invention, what I claim and desire to secure by Letters Patent is:

1. The combination in a high frequency 90 oscillator, of a plurality of stationary electrodes, a plurality of electrodes mounted to move in relation to the stationary electrodes, rods to which said movable electrodes are secured, solenoid magnets mounted with 95 relation to said rods, means on said magnets for variably gripping said rods, and means for adjusting the lift of the magnets.

2. The combination in a high frequency 100 oscillator, of a plurality of stationary electrodes, a plurality of electrodes mounted to move in relation to the stationary electrodes, rods to which said movable electrodes are secured, solenoid magnets mounted with 105 relation to said rods, movable cores mounted with the solenoids, means for adjusting the movement of said cores, and means on the cores for variably engaging the rods to lift the rods in unison with the cores.

3. The combination in a high frequency 110 oscillator, of a plurality of stationary electrodes, a plurality of electrodes mounted to move in relation to the stationary electrodes, rods to which said movable electrodes are secured, solenoid magnets mounted with 115 relation to said rods, movable cores mounted with the solenoids, extensions formed on the lower ends of the cores through which the electrode supporting rods extend which are adapted to variably grip the rods when the 120 solenoids are energized, and means for adjusting the upward movement of the cores with the solenoids.

4. The combination in a high frequency 125 oscillator, of a plurality of stationary electrodes, a plurality of electrodes mounted to move in relation to the stationary electrodes, rods to which said movable electrodes are secured, solenoid magnets mounted with 130 relation to said rods, movable cores mounted

with the solenoids, extensions formed on the lower ends of the cores through which the electrode supporting rods extend which are adapted to variably grip the rods when the 5 solenoids are energized, and adjusting screws for limiting the movement of the cores with the solenoids.

In testimony whereof I have hereunto set my hand in the presence of two subscribing witnesses.

CHARLES D. HERROLD.
